UNITED STATES PATENT OFFICE.

JOHN H. GRAHAM, OF BOSTON, MASSACHUSETTS.

CAR-TRUCK.

SPECIFICATION forming part of Letters Patent No. 570,473, dated November 3, 1896.

Application filed November 22, 1895. Serial No. 569,794. (No model.)

To all whom it may concern:

Be it known that I, JOHN H. GRAHAM, of Boston, in the county of Suffolk, State of Massachusetts, have invented certain new and useful Improvements in Car-Trucks, of which the following is a description sufficiently full, clear, and exact to enable any person skilled in the art or science to which said invention appertains to make and use the same, reference being had to the accompanying drawings, forming part of this specification, in which—

Figure 1 is a top plan view of the truck-frame; Fig. 2, a side elevation of the same; Fig. 3, a vertical transverse section taken on line $x-x$ in Fig. 2; Fig. 4, a like view taken on line $y-y$ in Fig. 2, and Fig. 5 a longitudinal section through the axle-box.

Like letters and figures of reference indicate corresponding parts in the different figures of the drawings.

My invention relates especially to improvements in the construction of car-trucks for use with electrically-propelled street-cars; and it consists in certain novel features hereinafter fully set forth and claimed, the object being to produce a simple, cheap, and effective device of this character.

The nature and operation of the improvement will be readily understood by all conversant with such matters from the following explanation:

In the drawings, A represents the frame of the truck considered as a whole. This comprises two metallic I-beams B, connected adjacent its ends by metallic tubing d, through which a rod f passes, said rods being held by nuts g, turned thereon outside the beams. Centrally the beams are connected by a metallic rod h, on which is secured a plate i. (See Fig. 1.) Between this plate and the beams tubes j are mounted on the rod h. Brace-rods k, bolted to the plate i, radiate therefrom and have their outer ends secured by bolts m to the beams. The pedestals C are bolted to the I-beams, one of the bolts m serving for this purpose. The axle-boxes D slide vertically between the pedestal-arms in the usual way.

To the outer ends of the I-beams, clips H are secured by bolts p. These clips have a horizontally-inclined eye q in their lower ends,

into which a tie-rod r is secured. This rod consists, preferably, of a metallic tubing for the purposes of lightening the frame, and a take-up screw and nut t is turned into the end thereof. Clips v in the lower ends of the pedestal-arms secure them to said tie-rods.

Upwardly-curved semielliptical leaf-springs w are secured centrally on the axle-boxes, their ends projecting through the pedestals, one of which is broken away at the left of Fig. 2 to show said spring.

At either side of the pedestal a clip K is secured to the I-beam and is pendent therefrom. These clips have an opening z, into which the ends of the semielliptical springs respectively project. A bolt 15, (see Fig. 3,) having an enlarged head 16, is dropped through the ends of the spring and bottom of the clip. On the lower ends of said bolts a base-plate 17 is held, between which and the clip bottom a coiled spring P is interposed, the strength of each sets of springs being less than that of these semielliptical springs. Two or three nested springs may be substituted for the single-coiled spring.

The axle-box D (shown in Fig. 5) has a groove 25 on its top to receive the semielliptical spring, and in general construction is of the ordinary form. Around the axle E, however, I dispose a collar 26, flanged at 27 and convex at 28. On the box I form an annular flange 29, and between said flange and the collar 28, I interpose a washer 30 of fibrous or other suitable material. This flange, when the parts are set up, throws against the convex face of the collar and is bent into the groove formed by the flange 27, serving as a dust-guard.

In the use of my improvement, the weight of the truck-frame is received by the semielliptical springs w through the coiled springs p, which are hung, as described, from the ends of said elliptical spring. A light load is thus readily cushioned by said coiled springs, and before the limit of said springs is reached the leaf-spring responds to the weight. The frame constructed of metallic tubes and the I-beam is extremely rigid for its weight, and a motor can be mounted on the cross-bars k, said bars serving as a support in addition to bracing the frame. The tubular tie-rod r, arranged in the manner described, also greatly strength-

ens the frame without adding materially to its weight.

The clips II K, supporting, respectively, the tie-rods or arch-bars and pedestal-springs, 5 afford a cheap, quick method of attaching the same to the beams.

Having thus explained my invention, what I claim is—

1. In a car-truck, the I-beam, side bar in combination with the tubular arch-bar and the clips, II, bolted to said side bar and in which said arch-bar is secured.
2. The frame, A, comprising the I-beams,

B, connected by tubes, d, and rods, f, h, the plate, i, and the radiating braces, k, connecting said plate and beams. 15

3. In a car-truck the axle, in combination with the axle-box, D, having a flange, 29; collar, 26, provided with the convex portion, 28, and the flexible washer, 30, in engagement 20 with said flange, substantially as described.

JOHN H. GRAHAM.
